METAL BENDING MACHINE

James C. Sweeney, Detroit, Mich., assignor to
 Ternstedt Manufacturing Company, Detroit,
 Mich., a corporation of Michigan

Application October 18, 1934, Serial No. 748,775

11 Claims. (Cl. 153—33)

This invention relates to a metal bending machine and more particularly to a bending machine for metal strips of channel section such as may be used for window glass frames.

5 It is an object of this invention to produce a machine that will bend a strip of metal which may be of channel section so that the original section of the strip is maintained and so that the bend is smooth and uncrinkled.

10 In the drawings:

Fig. 1 is a plan view of the machine.

Fig. 2 is a detail of the air control mechanism.

Fig. 3 is a fragmentary plan view showing the position of the die and the ironer toward the end 15 of the bending operation.

Fig. 4 is a fragmentary plan view showing the position of the various parts of the machine after the bending operation has been completed and before the work is discharged.

20 Fig. 5 is a side elevation of the machine.

Fig. 6 is a section along the line 6—6 of Fig. 4 immediately after the work has been bent and before the die is retracted to discharge the work.

Fig. 7 is a section along the line 7—7 of Fig. 6.

25 Fig. 8 is a detail view of one of the air cylinders for the ironer.

Fig. 9 is a detail of the work throw out device.

Fig. 10 is a detail of the bending die support slide.

30 Figs. 11 and 12 are details of the clamp for clamping the work to the die.

Fig. 13 is a diagrammatic showing of the air lines running to the several air cylinders.

35 Fig. 14 is a detail of a channel window frame which may be bent on this machine.

Fig. 15 is a section along the line 15—15 of Fig. 14.

40 Referring more particularly to the drawings the machine comprises a base 1 upon which is mounted a main air cylinder 2. The main air cylinder 2 is provided with a piston 3 having a connecting rod 4. The connecting rod 4 is connected to the die support plate 5 by the pin 6. The die 7, about which the metal is bent, is carried by support plate 5 which is slidably and reciprocably mounted in a suitable guideway 8 in the top 9 of the frame member 1.

45 The die 7, which is shown in the drawings for descriptive purposes only, is shaped to bend a length of channel section into the approximately U shaped frame 10 shown in Fig. 14. This U-shaped frame 10 is used as a frame for the swinging window glass in an improved window assembly. It is understood that the shape of

the die may be varied without departing from the spirit of the instant invention.

5 Since the work must be securely held to the die during the bending operation, a clamping device is provided for clamping the work to the die. This clamping device may take the form of a lever 11 pivotally mounted as at 12 to the block 13 which is fixed upon the die support plate 5. The lever 11 carries a removable clamping head 14. The clamping face 15 of the head 10 14 will vary with the contour of the work which is being bent. As herein shown (Fig. 15) the work is of channel section. The head 14 is provided with a flat working face 15 which engages against the bottom face 16 of the channel 10. 15

The clamp is operated by compressed air. To this end an air cylinder 17 is secured to the underside of the die support block 13. The air cylinder 17 is provided with a suitable piston and connecting rod 18, the outer end of which is 20 bifurcated and carries the pin 19 which engages the lever 11 in the slot 20 thus operatively connecting the plunger 18 with the clamping lever 11.

25 The bending of the work 10 about the die 7, which may be secured by screws to block 13, into the U-shaped frame 10 is accomplished during the projection of the die 7 by a pair of ironers 21. These ironers 21 are arranged to engage the work on opposite sides of the clamp 14 and bend the 30 same around the opposite edges of the die. Since the ironers 21 are each mounted and operated in the same fashion, only one will be described. Each ironer 21 is pivotally supported by a pin 22 between the spaced lugs 23 carried by the reciprocating cylinder 24. The reciprocating cylinder is carried by the slide or carriage 81 slidably mounted in the inclined guideway 25 (Figs. 1 and 7) in the top 9 of the supporting frame. The guideway 25 is positioned at an angle in the present 40 case of about 45° to the guideway 8 in which the die support plate or carriage 5 reciprocates.

45 As shown in Fig. 8 the top 9 of the frame work is provided with an upstanding bifurcated lug 26. The outer end of the connecting rod 29 for the 50 stationary piston 30 within the reciprocating cylinder 24 is adjustably secured to lug 26 by means of a pin 28 in one of the holes 27. A rod 31 is screwed or otherwise secured to the base of the reciprocating cylinder 24 and coil spring 32 is 55 threaded over the rod. Coil spring 32 is held on the rod 31 and in abutting relation with the lug 26 by the nut 33. This coil spring 32 is placed under compression as the cylinder 24 moves inwardly toward the die 7 and thus assists in the 55

retraction of the ironer 21 and cylinder 24 upon the completion of the bending operation. The stroke of the cylinder 24 can be increased or decreased by changing the effective length of the connecting rod 29 which is permitted by the adjusting holes 27 and pin 28. The ironer 21 is yieldably held in retracted or inoperative position by the coil spring 34. The working face of the ironer will vary in shape depending upon the section of the work which is to be bent. In the instant case the work 10 is of channel section. Consequently the ironer is provided with a working face in the form of a groove 35 which slidably receives the work and the working edge of the die during the bending operation.

The top of the table 9 is provided with an adjustable stop 36 (Fig. 1) against which the end of the work is placed prior to being clamped to the die 7. This insures proper positioning of the work relative to the die prior to the bending operation.

The work is bent during the projecting or outward stroke of the die 7. It is desirable that the work be automatically discharged from the die after being bent. To this end a block 37 is adjustably mounted upon the top 9 of the machine frame along each side of the guideway 8. The block 37 has pivotally mounted thereon (Fig. 9) as at 38 the work knockout dog 39. The inner face of the knockout dog 39 is provided with a groove 40 in which the dog engages the die 7. A convolute spring 41 yieldably holds the dog 39 against the side edge of the die or against the stop pin 42 when the die is projected.

The air control and air feed lines are diagrammatically shown in Fig. 13. The main air line 45 is connected with the main air cylinder 4 through a valve 46 and the lines 47 and 48. The main air line 45 is connected through the control valve 49 with the cylinder 17 by lines 50 and 51 and branch lines 52 and 53 and with cylinder 24 by lines 50 and 51 and branch lines 54 and 55. The valves 46 and 49 may be a well known commercial product purchasable upon the open market and since the valves per se do not form a part of the instant invention they will not be further described. The air lines connected with the movable cylinders 2, 24 and 17 may be flexible or rubber hose.

The valve 49 is controlled by the lever 56 and the valve 46 by the lever 57. The machine is started by manual operation of the levers 56 and 57 but automatically stops and discharges the work. The automatic control may take the form of a rod 58 which is slidably supported by a collar 59 fixed to the top 9 of the frame 1 and is slidably supported in the top 9 as at 60 (Fig. 1). The sliding rod 58 is provided with the adjustable arms 61 and 62 which may be held in their adjusted position by any suitable means such as a set screw. The rod 58 is also provided with the adjustable collars 63, 64 spaced on opposite sides of the support 59. A suitable coil spring 65 is threaded over the end of the rod 58 between the collar 63 and the support 59.

The rod 58 (Fig. 2) also carries an adjustable collar 66 which may be secured in its adjusted position by a set screw. This collar 66 slidably receives the straight end portion 67 of the bent rod 68. The portion 67 of the rod carries a collar 69 between which and the collar 66 is mounted a coil spring 70. The other straight end portion 71 of the rod 68 is provided with a hooked end 72 and is slidably mounted in a suitable support 73 as at 74. The arm 61 throws the lever 57 into

off position and the hooked end 72 of the rod 68 throws the valve control lever 56 to off position.

As shown in Fig. 10, the die support plate 5 has adjustably mounted on its underface as at 74, a rod 75 with a hooked end 76, Figs. 6 and 10. During the outward travel of the die support plate 5, the hooked end 76 of the rod 75 picks up the arm 62. The exact point at which the hooked end 76 picks up the arm 62 of the air control mechanism will be varied depending upon the length of the die and the size and type of work that is being bent.

The operation of the machine is as follows: In Fig. 1 the machine is shown in starting position with the die 7, ironers 21 and clamp 14 in retracted position. At this time the valve control levers 57 and 56 are in their extreme right position shown in Fig. 5 so that the main air line 45 is connected with line 48 through valve 46 and line 47 is open to atmosphere. The main air line 45 at this time is also connected through valve 49 with air lines 51, 52 and 55 with air lines 50, 53 and 54 open to atmosphere. The work which is in the form of a single strip of metal of channel section is fitted over the front edge of the die with the remote end of the work abutting against the stop 36 to insure the proper positioning of the work relative to the die. The operator next shifts lever 56 to the left into the dotted line position shown in Fig. 6. The shifting of the lever 56 to the left through the engagement with the hooked end 72 of the bent rod 68 shifts the rod 68 to the left thereby compressing the spring 70. At this time the main air line 45 is connected with air line 50 and with cylinders 24 and 17 through branch lines 53 and 54 thus causing the cylinders 24 to move inwardly along their trackways so that the ironers 21 engage the work 10 but do not start to bend the same. The ironers 21 are merely shifted toward the work so that they will be in position to bend the work about the corners and side faces of the die when it is projected. By shifting the lever 56 to the left the air is also admitted through line 53 to cylinder 17 which causes the clamp 14 to swing inwardly toward the die and clamp the work to the die as shown in Figs. 3 and 11. The work is now in position to be bent.

At this time the operator throws the lever 57 to the left in the position shown by the dotted lines of Fig. 6. This connects line 47 with the main air line 45 and opens line 48 to exhaust thereby admitting air into the left end of the cylinder 24 causing the plunger 4 and die 7 to be projected or travel outwardly to the right as indicated by the arrow Fig. 3. As the die approaches the ironers 21, the ironers 21 swivel about pins 22 from the position shown in Fig. 1 to that shown in Fig. 3, that is, the ironers 21 adjust themselves so that they follow the contour of the corners and side edges of the die 7 and bend the work 10 against the corners and side edges of the die. As the die travels outwardly the rod 75 picks up the arm 62, Figs. 4 and 6, thereby shifting the rod 58 to the right until the arm 61 engages lever 57. The hooked end of rod 75 is already in engagement with the lever 56 and the spring 70 is partially compressed. As the rod 58 travels to the right the compression of the spring 70 is increased until the resistance of the lever 56 is overcome whereupon the lever 56 is thrown over to the right to the position shown in full lines, Fig. 6. This opens line 50 to atmosphere and connects main line 45 with line 51 and branch lines 52 and 55 thereby retracting

the cylinder 24 and ironers 21 and the clamp 14 as shown in Fig. 4. At this time the die 7 is at the end of its outward or projected stroke and the lever 57 is in the vertical position shown in Fig. 6.

5 With the valve lever 57 in vertical position the main air line 45 is shut off and both lines 47 and 48 are open to atmosphere. The operator next throws lever 57 manually to the right into the dotted line position indicated (Fig. 6). This 10 connects main air line 45 with line 48 which permits air to flow into cylinder 42 thereby retracting the die 7 to its original or starting position, line 47 remaining open to atmosphere. If desired, the air control mechanism can be adjusted 15 so that as the die 7 reaches the end of its outward stroke, the arm 61 will throw the lever 59 over center to the right hand position indicated in the dotted lines of Fig. 6, thereby exhausting line 47 and connecting line 48 with line 45 causing the 20 die to be automatically retracted upon completing its outward stroke. With such an arrangement the die would begin its return stroke at the same time that the clamp 14 and ironers 21 were retracted but the clamp 14 would be completely 25 retracted before the work came in contact with the knockout dogs 39.

As the die 7 is retracted the knockout dogs 39 slidably engage the side edges of the die in the groove 40. Shortly after the clamp 14 is released 30 and shortly before the die reaches its fully retracted position the ends of the work, which is now bent into a U, engage the knockout dogs 39 which disengage the work from the die as indicated in the dotted lines, Fig. 1. The position of 35 the work 10 after being bent and before the die starts on its return stroke is indicated by dotted lines, Fig. 4, and the position of the work 10 after the ends of the channel frame have been engaged by the knockout dogs 39 at the end of the 40 return stroke of the die 7 is indicated in the dotted lines, Fig. 1.

Each ironer 21 while inoperative is held in retracted position against a stop 80 on the reciprocating carriage 81 by a coil spring 34 (Figs. 1 and 45) so that the working faces 35 of the ironers are substantially parallel to the work 10 when clamped to the front working face of the die 7. As the die 7 is projected on the bending stroke, 50 the ironers first engage the work and then swivel about the corners of the die, while bending the work along the working face of the die, to a position parallel to the side working faces of the die as shown in Fig. 3.

I claim:—

55 1. A bending machine for bending a metal strip comprising a reciprocating die having a working face along which the metal is bent, means for securing the work to the die, a yieldable ironer reciprocably mounted at an angle to the reciprocable die and projectable into the pathway of the die whereby as the die is projected the yieldable ironer engages the work and bends the same along the working face of the die, and means engageable with the work during the 60 retracting stroke of the die for disengaging the bent work from the die.

2. A metal bending machine comprising a support having a pair of rectilinear guideways positioned at an angle to each other, a reciprocable carriage mounted in each of the said guideways, a die about which the metal is bent mounted on one of the said carriages and an ironer mounted on the other of said carriages, means for yieldably projecting the carriage for the ironer toward the said guideway for the die, and means

for projecting the die whereby the ironer yieldably engages the work and bends the same about the working face of the die during the outward stroke of the said die.

3. A metal bending machine comprising a support having a pair of rectilinear guideways positioned at an angle to each other, a reciprocable carriage mounted in each of the said guideways, a die about which the metal is bent mounted on one of the said carriages and an ironer 10 mounted on the other of said carriages, means for yieldably projecting the carriage for the ironer toward the said guideway for the die, means for releasably securing the said work to the die, and means for projecting the die whereby 15 the ironer yieldably engages the work and bends the same about the working face of the die during the outward stroke of the said die.

4. A metal bending machine comprising a support having a pair of rectilinear guideways positioned at an angle to each other, a reciprocable carriage mounted in each of the said guideways, a die about which the metal is bent mounted on one of the said carriages and an ironer swivelly mounted on the other of said carriages, means 20 for yieldably projecting the carriage for the ironer toward the said guideway for the die, and means for projecting the die whereby the ironer yieldably engages the work and bends the same about the working face of the die during the 25 outward stroke of the said die.

5. A metal bending machine comprising a support having a pair of rectilinear guideways positioned at an angle to each other, a reciprocable carriage mounted in each of the said guideways, 30 a die about which the metal is bent mounted on one of the said carriages and an ironer swivelly mounted on the other of said carriages, means for yieldably projecting the carriage for the ironer toward the said guideway for the die, means 35 for projecting the die whereby the ironer yieldably engages the work and bends the same about the working face of the die during the outward stroke of the said die, and resilient means for 40 yieldably holding the said ironer in retracted position on the carriage whereby the working face of the ironer is in position for engagement with, and bending, the work when the die is projected.

6. A metal bending machine comprising a support having a pair of rectilinear guideways positioned at an angle to each other, a reciprocable carriage mounted in each of said guideways, a die about which the metal is bent mounted on one of said carriages and an ironer, swivelly mounted on the other of said carriages, a clamp 50 for clamping the work to the working face of the die, means operated by fluid under pressure in the form of a cylinder and piston operatively connected to the ironer carriage and a cylinder and piston operatively connected to the said 55 clamp for operating the said carriage and the said clamp, valve means for controlling the said fluid operated means for retracting the work clamp and the said ironer at the completion of the bending operation, and means engageable with the work during the retracting stroke of the die 60 for ejecting the work from the die.

7. A metal bending machine comprising a support having a pair of rectilinear guideways positioned at an angle to each other, a reciprocable carriage mounted in each of said guideways, a die about which the metal is bent mounted on one of said carriages and an ironer swivelly mounted on the other of said carriages, a clamp 70 for clamping the work to the working face of the 75

- die, means operated by fluid under pressure in the form of a cylinder and piston operatively connected to the ironer carriage and a cylinder and piston operatively connected to the said clamp for operating the said carriage and the said clamp, valve means for controlling the said fluid operated means for retracting the work clamp and the said ironer at the completion of the bending operation, and a pivoted knockout dog positioned along one side of the guideway for the carriage upon which the die is mounted arranged to engage the end of the work during the retracting stroke of the die to eject the same from the die.

8. A metal bending machine for bending a single length of metal into a U frame comprising a support having a rectilinear guideway, a reciprocating carriage for the said guideway, a die mounted on the said carriage having front and side work faces, a clamp for clamping the work to the front face of the die with the ends of the work projecting beyond the side faces of the die, a pair of rectilinear guideways positioned one on each side of the guideway for the die carriage and at an angle to the first mentioned guideway, a carriage for each of said pair of guideways, an ironer swivelly mounted on each of said carriages, and means for yieldably projecting the said carriages and ironers so that the ironers project into the pathway of the die whereby upon the projecting stroke of the die the said ironers engage the work and bend the same about the working faces of the die.

9. A metal bending machine for bending a single length of metal into a U frame comprising a support having a rectilinear guideway, a reciprocating carriage for the said guideway, a die mounted on the said carriage having front and side work faces, a clamp for clamping the work to the front face of the die with the ends of the work projecting beyond the side faces of the die, a rectilinear guideway positioned on each side of the guideway for the die carriage and at an angle to the said guideway, a carriage for each of said guideways, an ironer swivelly mounted on each of the said carriages, resilient means for yieldably holding each ironer in retracted position on its said carriage whereby the working face of the ironer is substantially parallel to the work which is clamped on the die, and means for yieldably projecting the said carriages and ironers with the ironers projecting into the pathway of the die whereby when the die is projected the working faces of the ironers engage the work on opposite sides of the clamp and the ironers, while bending the work along the working faces of the die, swivel from their retracted position to a position with their working faces parallel to the side faces of the die.

10. A metal bending machine for bending a single length of metal into a U frame comprising a support having a rectilinear guideway, a reciprocating carriage for the said guideway, a die mounted on the said carriage having front and side work faces, a clamp for clamping the work to the front face of the die with the ends of the work

work projecting beyond the side faces of the die, a rectilinear guideway positioned on each side of the guideway for the die carriage and at an angle to the said first mentioned guideway, a reciprocable carriage for each of said guideways, an ironer swivelly mounted on each of the said second mentioned carriages, resilient means for yieldably holding each ironer in retracted position on its carriage whereby the working face of the ironer is substantially parallel to the work which is clamped on the die, means for yieldably projecting the said carriages and ironers so that the ironers project into the pathway of the die whereby when the die is projected the working faces of the ironers engage the work on opposite sides of the clamp and swivel from their retracted position to a position parallel to the side faces of the die while bending the work along the working faces of the die, means for retracting the ironers and the clamp at the completion of the bending operation, and knockout means positioned along the side edges of the guideway for the die carriage for engaging the ends of the U frame upon the retracting stroke of the die after the metal has been bent to eject the same from the die.

11. A metal bending machine for bending a single length of metal into a U frame comprising a support having a rectilinear guideway, a reciprocating carriage for the said guideway, a die mounted on the said carriage having front and side work faces, a clamp for clamping the work to the front face of the die with the ends of the work projecting beyond the side faces of the die, a rectilinear guideway positioned on each side of the first mentioned guideway for the die carriage and positioned at an angle to the said guideway, a reciprocable carriage for each of said second mentioned guideways, an ironer swivelly mounted on each of the said carriages, resilient means for yieldably holding each ironer in retracted position on the said carriage whereby the working face of the ironer is substantially parallel to, and in position to receive, the work which is clamped on the die, means for yieldably projecting the said carriages and ironers so that the ironers extend into the pathway of the die whereby when the die is projected the working faces of the ironers engage the work on opposite sides of the clamp and swivel from their retracted position to a position parallel to the side faces of the die while bending the work along the working faces of the die, means operated by fluid under pressure in the form of a cylinder and piston operatively connected to each ironer carriage and a cylinder and piston operatively connected to the said clamp, valve means for controlling the said pistons and cylinders for retracting the work clamp and the said ironers at the completion of the bending operation, and a pivoted knockout dog positioned on each side of the die carriage guideway for engagement with the ends of the U frame at the completion of the bending operation and upon the return stroke of the die for ejecting the U frame from the die.

JAMES C. SWEENEY.
